Specification for Design.

Patented Apr. 13, 1920.

Application filed February 24, 1919. Serial No. 278,994. Term of patent 7 years.

To all whom it may concern:

Be it known that I, ALBERT F. SAUNDERS, a citizen of the United States, residing at 106 Rugby road, city of Syracuse, county of Onondaga, and State of New York, have invented a new, original, and ornamental Design for a Goblet, of which the following is a specification, reference being had to the accompanying drawing, forming a part thereof, wherein—

Figure is a side elevation of the goblet, Fig. 2 is a top plan view thereof.

I claim:

The ornamental design for a goblet, substantially as shown.

In testimony whereof, I have hereunto signed my name at East Syracuse, in the county of Onondaga and State of New York this 31st. day of January 1920.

ALBERT F. SAUNDERS.
